UNITED STATES PATENT OFFICE

CHARLES H. BERGQUIST, OF OKMULGEE, OKLAHOMA, ASSIGNOR OF ONE-HALF TO
EMERY A. LOCKE, OF OKMULGEE, OKLAHOMA

COUNTERBALANCE

Application filed February 6, 1929. Serial No. 337,923.

This invention relates to counterbalances for use in connection with the band wheel assemblies of pumping wells.

Briefly stated, one of the objects of the invention is to provide a band wheel assembly in which a special counterbalance and the usual beam operating crank are secured on opposite ends of the band wheel shaft, to reduce the wear on the band wheel shaft and 10 the bearings therefor.

Another aim is to provide a counterbalance in which the main weighted portion thereof may be connected to or disconnected from the band wheel shaft with a minimum of effort and loss of time so that when it is necessary to interrupt pumping for the purpose of removing either the sucker rods or the tubing, the accruing loss of production will be minimized, it being noted in this particular that 20 the disconnection of the weighted portion of the counterbalance is required to adapt the band wheel assembly to the removal and installation of the rods and the tubing. More specifically, the invention will be found to 25 provide easily operated means by which the main weighted portion of the counterbalance may be raised from the derrick floor to an operative position or lowered from such operative position and subsequently disconnected from the attaching portion of the counterbalance to allow the band wheel assembly to be used to advantage for other than pumping purposes.

Other objects and advantages will be apparent during the course of the following description.

In the accompanying drawings forming a part of this application and in which like numerals are employed to designate like 40 parts throughout the same,

Figure 1 is a side elevation of the improved band wheel assembly, the beam operating crank and the improved counterbalance being shown on opposite ends of the band wheel shaft,

Figure 2 is a fragmentary side elevation taken at right angles to Figure 1 and illustrating the improved counterbalance in an operative position,

Figure 3 is a fragmentary side elevation 50 illustrating the weighted portion of the counterbalance in position to be lifted into close engagement with the attaching portion of the counterbalance, the same position being occupied by the weighted portion of the counterbalance during the removal of the same 55 to adapt the band wheel assembly to purposes other than pumping,

Figure 4 is a group perspective illustrating 60 the weighted portion of the counterbalance at rest on the floor and a sufficient distance below the attaching portion thereof to permit of the free turning of the shaft of the band wheel assembly for purposes other than pumping.

In the drawings wherein for the purpose 65 of illustration is shown a preferred embodiment of the invention, the numerals 5 and 6 designate jack posts which are, of course, suitably braced as indicated at 4. As shown in 70 Figure 1, the upper portions of the posts 5 and 6 are provided with sectional bearings 7 and 8 respectively and through which the band wheel shaft 9 extends. As usual, the band wheel 10 is secured on the shaft 9 between the posts 5 and 6.

One end of the shaft 9 is provided with the customary crank 11 to which the beam operating link 12 is pivoted, while the opposite end of the shaft is provided with the improved counterbalance. This arrangement 80 distributes the strain on the assembly, especially the bearings 7 and 8.

The improved counterbalance comprises an attaching member 14 keyed or otherwise permanently secured on the shaft 9 and adapted 85 for connection with the weighted or body portion 16 through the medium of combination lifting and attaching bolts or arms 18. The body 16 of the counterbalance comprises a 90

plurality of sections or segments having interfitting or interlocking means by which shifting of one section with respect to the others is inhibited.

5 As shown in Figure 4, the outermost section 20 of the body 16 is extended beyond the edges of the contiguous section and is provided with sockets 22 within which the apertured heads of the bolts 18 are pivoted as indicated at 24. In passing, it might be noted that the lower walls of the sockets 22 are in the path of and are adaptable for engagement by the bolts or arms 18 and limit the extent to which the bolts 18 may swing outward to 15 an inoperative position, the restriction in the outward pivotal movement of the bolts 18 holding the bolts in position for ready return to the grooves 26 in opposite edges of the body 16.

20 The attaching member 14 is provided with grooves 28 adapted for registration with the grooves 26 to receive the bolts 18.

In initially installing the improved counterbalance, the attaching member 14 thereof 25 is connected permanently to the shaft 9 and the weighted or main body portion 16 is then positioned directly beneath the attaching member. After this, the arms 18 are swung into the grooves 26 and 28 and the nuts 30 advanced to raise the body portion 16 from the 30 derrick floor into close and rigid engagement with the attaching member 14. That is to say, the advancement of the nuts 30 raises the body 16 to the operative position illustrated 35 in Figure 2 so that a firm interlocking connection is established between the body and the attaching member 14 and between the sections of the body itself.

With particular reference to the means by 40 which the sections of the counterbalance are held against shifting with respect to each other, it will be seen that when the pivoted arms 18 are received within the communicating grooves 26 and 28 the same cooperate 45 actively with the tongue and groove connections between the sections to hold the sections in place. Thus, the arms 18 serve the triple purpose of providing for raising and lowering the weighted portion 16, securing 50 the weighted portion rigidly to the attaching member 14 and finally cooperating with the tongue and groove connections in holding the sections against movement with respect to each other. To this latter end, the communicating 55 grooves 26 and 28 may be made sufficiently narrow to dispose the side walls thereof close enough to the arms 18 to avoid appreciable movement of one section of the body with respect to the others.

60 For the original installation of the counterbalance, calculation may be made as to the weight required and, of course, such calculation takes into consideration, among other things, the weight of the column of fluid to be 65 lifted. It is a simple matter to provide the

desired weight by the addition or removal of one or more sections of the body 16.

Should it be required to interrupt pumping to withdraw the sucker rod or the tubing, the main body portion 16 may be lowered to the position suggested in Figure 3 by simply backing up the nuts 30 until the body 16 rests on the derrick floor with the uppermost section thereof a sufficient distance below the attaching portion 14 to allow of the free turning of the shaft 9. To provide for the convenient application and removal of the body or weighted portion 16, the bolts 18 are made long enough to extend to a point above the attaching member when the body 16 is at rest on the derrick floor.

During the use of the band wheel assembly for the purposes other than pumping, such for example as the cleaning out of the well, the weighted portion 16 will remain at rest in the position illustrated in Figure 4 and to provide for the resumption of pumping, the bolts 18 are moved up to parallel positions within the communicating grooves 26 and 28 so that the subsequent tightening of the nuts 30 will raise the weighted portion to operative position.

With reference to the foregoing description taken in connection with the accompanying drawings, it will be apparent that the improved counterbalance may be applied or removed with a minimum of effort and loss of time so that the period of shut down of the well and consequent loss of production is not prolonged unduly. The fact that the attaching member 14 may be secured permanently on the shaft 9 makes it possible to provide a very rigid connection between these parts so that the counterbalance is not allowed to work loose.

The improved counterbalance might be defined as a sectional body in which one of the sections thereof is provided with means by which the same may be connected permanently to the band wheel shaft of a band wheel assembly, the main weighted portion of the counterbalance being attached securely to the aforesaid end section and the various sections of the counterbalance held in interlocked position to give the effect of a one piece body.

Having thus described the invention, what is claimed is:

1. In a counterbalance for use in connection with the band wheel shaft of a band wheel assembly, a body comprising a plurality of sections and an attaching portion, the attaching portion being provided with means whereby the same may be secured in a relatively permanent manner to a band wheel shaft, and bolts having pivotal connection with one of the sections and being provided with means engaging said attaching portion, said attaching portion and the sections of said body being provided with means

- receiving said bolts whereby the sections are held against movement with respect to each other and to said attaching portion.
2. In a counterbalance for use in connection with the band wheel shaft of a band wheel assembly, a body comprising a plurality of interlocked sections and an attaching portion, the attaching portion and said sections being provided with grooves, and bolts received in said grooves and having fastening devices engaging said attaching portion and forming a means by which the sections of said body may be raised into interlocking connection with the attaching portion, said bolts being connected to the outermost section of said body.
3. In a counterbalance for use in connection with balance wheel shafts, a body having a plurality of sections and an attaching portion, said attaching portion and said sections being provided with oppositely located grooves, and bolts movable laterally into said grooves to hold the sections against movement with respect to each other and being provided with fastening devices engaging said attaching portion and forming a means by which the sections of the body may be raised to a position in firm connection with said attaching portion and lowered to a point spaced below the same, said bolts being pivotally connected to the outermost section of said body.
4. In a counterbalance for use in connection with balance wheel shafts, a body comprising a plurality of sections and a separate attaching portion, the attaching portion being provided with means whereby the same may be secured in a relatively permanent manner to the band wheel shaft, the opposite edges of said sections and said attaching portion being provided with alined grooves, bolts detachably received in said grooves to join the sections and being provided with means to raise the sections into firm engagement with said attaching portion and to lower the sections to a point spaced below the attaching portion, said bolts having pivotal connection with the outermost section of said body, there being means limiting the outward pivotal movement of said bolts.
5. In a counterbalance for band wheel shafts, a body consisting of a plurality of sections, the outermost one of which is formed with extensions having sockets, arms having the outer terminal portions thereof pivoted to said extensions and positioned in said sockets, and an attaching member having means whereby the same may be rigidly attached to the shaft of a band wheel, there being means whereby said arms may be detachably connected to said attaching member.
6. In a counterbalance for band wheel shafts, a body consisting of a plurality of sections, the outermost one of which is formed with extensions having sockets, arms having the outer terminal portions thereof pivoted to said extensions and positioned in said sockets, and an attaching member having means whereby the same may be rigidly attached to the shaft of a band wheel, said arms having means whereby the same may be secured rigidly to the shaft of a band wheel, said arms being provided with means to secure the inner end of said body in pressure engagement with said attaching member.
7. In a counterbalance for the shaft of a band wheel, a body consisting of a plurality of sections having grooves, arms pivotally connected to said body and extending through said grooves, and an attaching member having means whereby the same may be attached to the shaft of a band wheel, said arms being provided with means to secure the innermost section of said body in pressure engagement with said attaching member.
8. In a counterbalance for band wheel shafts, a body consisting of a plurality of sections having grooves opening out through opposite ends thereof, arms connected to said body and extending through said grooves, and an attaching member having means whereby the same may be secured rigidly to the shaft of a band wheel, said arms being provided with means to secure the innermost section of the body in pressure engagement with said attaching member and to rigidly connect the sections of the body.
9. In a counterbalance for band wheel shafts, a body consisting of a plurality of sections having grooves opening out through opposite ends thereof, arms connected to said body and extending through said grooves, and an attaching member having means whereby the same may be secured rigidly to the shaft of a band wheel, said arms being provided with fastening devices engaging said attaching member and forming a means to secure the innermost section of the body in direct pressure contact with said attaching member and to rigidly connect the sections of the body, said arms being removable laterally from said grooves.
10. In a counterbalance for band wheel shafts, a body of elongated formation and being provided in opposite sides thereof with longitudinal grooves, arms pivotally connected to said body and adapted to be swung into said grooves, and an attaching member having means whereby the same may be secured rigidly to the shaft of a band wheel, said arms being provided with means to secure the inner end of said body in pressure engagement with said attaching member.
11. In a counterbalance for the shaft of a band wheel, an attaching member having means whereby the same may be secured rigidly to the shaft of a band wheel, and a body of elongated formation adapted for direct engagement with the attaching member,

the engaging portions of said body and said attaching member being provided with interlocking means, and arms pivotally connected to said body and having means whereby the 5 same may be connected to said attaching member to rigidly connect the body to the attaching member, said body being provided with grooves opening out through opposite sides thereof and detachably receiving said 10 arms.

In testimony whereof I affix my signature.
CHARLES H. BERGQUIST.
